UNITED STATES PATENT OFFICE.

JAMES F. O'BRIEN, OF LOS ANGELES, CALIFORNIA.

CARTRIDGE-LOADING MACHINE.

1,126,651.

Specification of Letters Patent.

Patented Jan. 26, 1915.

Application filed December 16, 1913. Serial No. 807,018.

To all whom it may concern:

Be it known that I, JAMES F. O'BRIEN, a citizen of the United States, residing at Los Angeles, in the county of Los Angeles, State of California, have invented new and useful Improvements in Cartridge-Loading Machines, of which the following is a specification.

This invention relates to a machine for filling paper cartridges with explosive or the like; and the invention consists in the certain combinations and the details herein-after pointed out, forming a machine by which cartridges may be safely, easily and quickly loaded. The machine is preferably semi-automatic in operation, parts of its workings being entirely automatic and other parts being preferably operated by hand.

My machine includes the fundamental combinations as here described. I provide a plurality of cartridge holders which are adapted to hold a number of cartridges in vertical position ready to be filled with explosive. Above each cartridge there is a plunger or tamper adapted to fall downwardly into the cartridge and tamp the explosive therein, the weight of the tamper being suited to the work in hand. The plungers are arranged so as to normally fall freely and are periodically raised by a vertically reciprocating cross-head frame. Means are provided for feeding explosive to the various cartridges, and as the cartridges are filled up, the point to which each individual plunger or tamper will fall is constantly elevated. When any of the cartridges are completely filled, the corresponding plunger will fall only to a corresponding lowermost point; and when this occurs, there is mechanism on the reciprocating cross-head which picks up the plunger when the cross-head is at its lowermost point and carries the plunger upwardly through a movement considerably above its normal up and down movement. This raised movement of each individual plunger is used to actuate a means controlling the feed of explosive to the corresponding cartridge, the feed being immediately shut off so that the cartridge receives no further explosive. When all of the cartridges and all of the plungers are hung up and the feed of explosive completely shut off, the operator moves the filled cartridges to a point where the cartridges may be closed, at the same time moving a fresh set of empty cartridges into

place to be filled. A new filling operation then starts and the set of cartridges which has been filled is closed by suitable manually operated apparatus. The cartridge holders are arranged about a wheel or drum in longitudinal rows spaced equally distant from each other about the central axis; and advancement of the holders is caused by rotation of this drum or wheel. When the machine is in continuous operation, there is one set of cartridges being filled, another set being closed (or more properly speaking, there are two sets going through two separate closing operations), and there is another set being discharged from the machine. The set of holders in the position immediately prior to the loading position are open so that they may be filled by an attendant.

It will be understood that the construction herein described is composed almost entirely of non-metal parts, entirely eliminating danger of ignition of the explosive through friction.

The details of construction and operation of my improved machine are more fully set forth in the following specification, and illustrated in the accompanying drawings, in which,

Figure 1 is a vertical section of my improved machine. Fig. 2 is a section taken as indicated by line 2—2 of Fig. 1. Fig. 3 is a partial front elevation as indicated by line 3—3 of Fig. 1. Fig. 4 is a plan taken as indicated by line 4—4 of Fig. 1. Fig. 5 is a detail section taken as indicated by line 5—5 of Fig. 2. Fig. 6 is a perspective detail illustrating the cartridge holders and cartridge closing means. Fig. 7 shows the stages by which the cartridge end is folded to close it. Fig. 8 is a detail section taken as indicated by line 8—8 of Fig. 1, showing the cartridge closing means.

In the drawings my machine is illustrated as being mounted upon a suitable frame 10 of any desired size and arrangement. In the upper part of the frame there is carried a main shaft 11 equipped with driving pulley 12 and clutch 13 for delivery of power to the machine. Balanced cranks 14 are mounted upon the ends of the drive shaft 11 and connecting rods 15 connect the cranks with oscillating levers 16 pivoted at 17 to the frame. These oscillating levers cause the reciprocation of the important parts of the machine and cause operation of the

feeder. The feeder includes a feed box 17 which may be supplied with explosive in any desired manner, the bottom of the said box being formed by a belt 18 which is intermittently moved in the direction indicated by the arrow in Fig. 1. This belt 18 passes over idler wheel 19 and a drive wheel 20. Drive wheel 20 is driven from the lever 16 through the medium of ratchet mechanism 21 and connecting rod 22 may be connected to the lever 16 at any of various holes 23 in the lever; providing for different strokes of the ratchet mechanism and thus providing for different feeds of explosive.

By proper arrangement of the feeding mechanism the amount of explosive fed out of the hopper may be regulated to suit the capacities of the cartridges. At the front of the hopper 17 there is arranged a plurality of feed gates 25, one for each of the individual cartridge holders. In the present machine, I have shown a capacity of fifteen cartridges; and it will be understood that there are fifteen separate and distinct mechanisms for controlling supply of explosive to the cartridges and as many separate and distinct mechanisms for actuating said feed control and for tamping the explosive down in the cartridges.

In the lower part of the frame, a horizontal shaft 30 is mounted to carry the cartridge holders hereinbefore referred to. In the present machine there are six rows of cartridge holders arranged around the shaft 30; and each row of cartridge holders comprises the following described parts. The cartridge holders themselves are divided into halves 31 and 32, the half 32 being mounted upon backboard 33 which is supported by arms 35 from the central hub structure 34 of the drum or wheel. The backboard 33 and the holder halves attached to it are immovable with relation to the wheel. The other holder halves 30 are mounted upon backboard 36 which is pivotally connected with the hub structure 34 by pivoted arms 37. The parts are all so arranged that the cartridge holders may be opened to the position shown at "F" in Fig. 1 or may be closed to the position shown at "B" in that figure. At each end of each row of cartridge holders there is a suitable clamp 43 for holding the cartridge holders closed. This clamp is pivoted at 40 to the backboard 36 and has a shoulder 41 which catches over the back face of backboard 33 when the holder halves are closed together. A rod 42 is mounted in the ends of the clamps 43 connecting the swinging ends of the two clamps for each row of holders. The ends of this rod 42 project and are adapted to be engaged by stationary cams 44 when the parts are between positions "E" and "F" shown in the lower part of Fig. 1. Rotation of the wheel or drum in the direction indicated

engages the ends of the rod 42 with the cams 44 and cause the rod and the clamps to be pushed in the direction indicated by the arrow and causes the holder halves to be freed so as to drop open. The lower halves of the holders drop down to the positions illustrated at "F" at the left in Fig. 1 and allow the cartridges to slide out.

Each holder has a bore made up of two semi-cylindrical channels 45 in each holder half, the diameter of the bore corresponding to the cartridges filled in the machine. The cartridges are put into the holders when the holders are in the position designated "A" in Fig. 1, this operation being done by an attendant upon the machine. The cartridge holder wheel is turned by hand and the cartridges are next brought to the position designated "B," in which position they are upright. The cartridges 50 are then in a position to be filled. Funnel frame 51 is pivoted at 52 on the main frame and has a handle 53 so that it may be lifted and lowered. The funnel frame contains a plurality of funnels 54, one for each cartridge holder; and when the funnel frame is in the position shown in Fig. 1, two end pieces 51a fit between the ends of backboards 33 and 36, as shown in Fig. 5, so as to register the cartridge holders in place. The paper cartridge projects above the upper end of the cartridge holder, and a small thimble 55 is located at the bottom of each funnel 54 and adapted to enter the upper end of each cartridge so that all of the explosive entering the funnel 54 will be directed into the cartridge. The funnels 54 are arranged directly beneath the respective feed gates 25, (see Fig. 2), so that the feed coming under any one of the gates 25 will fall into the corresponding funnel 54 and pass into the corresponding cartridge 50.

The main frame 10 contains vertical slide ways 60 to guide reciprocating cross-head frame 61. This cross-head frame 61 is essentially composed of upper and lower horizontal bars 62 and 63 and vertical side bars 64. Connecting links 65 connect the cross-head with levers 15 so that by the oscillation of the levers 16 the cross-head is reciprocated vertically. In the drawings the cross-head is shown in its uppermost position. The cross-head frame has a plurality of guide holes 66 in its upper and lower bars for the plungers 67. Plungers 67 may be made of gas pipe or any other suitable material and are equipped with wooden tampers 68 on their lower ends. The wooden tampers may have tips 69 of leather or the like to directly strike upon the explosive in the cartridges 50. Plungers 67 are loose in the cross-head frame; reciprocation of the cross-head frame does not necessarily cause reciprocation of the plungers. The speed of op-

eration is such that the down stroke of the cross-head frame will allow the plungers to fall and strike the explosive in the cartridges 50; and the impact may be regulated by 5 regulating the weight of the plunger. If the plungers are made of gas pipe, their upper ends may be equipped with collars 70, and blocks 71 are then placed immediately beneath the collars tight on the plungers. 10 These blocks 71 normally rest upon spring boards 72 carried upon the upper bar 62 of the cross-head frame, the spring boards being provided as shock absorbers. The blocks 71 are preferably squared as is shown in 15 Fig. 4. Guide posts 73 are mounted upon the bar 62 so as to keep the squared blocks 71 from turning. In front of each plunger 67 and its block 71 there is a pivoted hanger post 74 with a counterweight 75 giving the 20 post a tendency to tip in the direction indicated toward the block 71. When any one cartridge has been filled up to its capacity (even with the top of the cartridge holder) the plunger and tamper for that particular 25 cartridge are only falling a short distance below the position shown in Fig. 1; and the normal downward movement of the cross-head frame will carry the hanger post 74 down to such a point that its upper end will move in under the lower edge of the block 71. The subsequent upward movement of the cross-head frame will carry the plunger upwardly to a position high enough so that the upper edge of the block 71 will strike 30 the pivoted gate lever 80 and cause it to be raised so that finger 81 may enter beneath its front lower edge and hold it in its raised position. 35 The gate levers 80 have weights 82 which normally hold them at their lower positions, and are pivoted on a suitable board 83 in the manner illustrated. Connecting rods 84 extend from the back ends of the individual gate levers directly to the corresponding gates 25. When the gate levers 80 are hung up on fingers 81, the gates 25 are closed; when the levers are in the position shown in Fig. 1 the gates 25 are opened. The plungers 67, hanger posts 74, fingers 81, gate 40 levers 80 and gates 25 are all individual parts, there being a complete and independent set of these parts provided for each and every cartridge holder. It will be seen that the action of each plunger 67 is independent of action of all the others, so that when any cartridge is filled to its predetermined capacity the individual mechanism for that cartridge will act to stop the corresponding powder supply. The parts may be arranged 45 and regulated so that the supply is accurately cut off when the cartridge is filled with the exact amount required. When all of the cartridges are filled, all the plungers hung up and the powder supply completely 50 shut off, then the funnel frame 51 may be 55 raised and the cartridge holder wheel rotated through one-sixth revolution to bring a fresh set of cartridges into position to be filled. Immediately this is done, the operation may be commenced and completed as 60 before. In order to commence a new filling operation it is only necessary that plungers 67 and the gate levers 80 be released and allowed to come to their normal position shown in Fig. 1. The fingers 81 are loosely 65 mounted in a finger carrier 90 pivoted at 70 91 to the frame. Connecting rods 92 connect the carrier 90 with manually operable pivoted frame 93 having a handle bar 94 extending completely across the machine in 75 a position to be conveniently reached by the operator. Pushing rearwardly in the direction indicated on the bar 94 throws the finger carrier 90 in the direction indicated 80 and throws the finger 81 from beneath the 85 gate levers 80, allowing the levers 80 to fall to their normal positions and open the gates 25, so that feeding of the explosive again commences. At the same time, the rearward movement of the bar 94 strikes blocks 90 95 on the lower ends of hanger posts 74 and moves these posts to their normal positions, allowing the plungers 67 to drop to their 95 normal positions. The counter-balance weights 14^a on the cranks 14 provide that the machines shall always come to rest in the position shown in Fig. 1, so that the above described operations may be easily accomplished. 100 During the operation of filling the next set of cartridges, the ones previously filled pass through the closing operations. The mechanism for effecting these operations is now described. A pedal frame 100 is pivotally mounted in the lower part of the 105 main frame with a pedal bar 101 across its front. At its rear end this pedal frame carries a slider bar 102 whose upper end 103 is conveniently guided between a boss or shoulder 104 and end 105 of funnel frame 110 51. The bar 103 carries a trip finger 106 which engages the back edge of folder bar 107 pivoted at 108 to the frame. This bar 107 carries two sets of folder fingers 109 and 110. On the upward movement of the 115 slider bar 102, the bar is turned in the direction indicated so that the fingers 109 press one side of the end of the cartridge down flat onto the explosive therein. This stage of the cartridge is shown in Fig. 7 at 120 "G". The trip finger passes the bar 107 and on its return movement it turns the folder bar in the opposite direction so that the folder finger 110 presses the opposite side of the projecting end of the cartridge 125 down flat. The two lateral sides of the projecting cartridge end are then left projecting as shown in Fig. 7 at "H"; and upon the next rotary movement of the cartridge holder these projections are carried into en- 130

gagement with folding ribs 111^a and 111^b where they are forced down flat and the cartridge comes to position "D" with the cartridge ends folded practically flat over the explosive. Figs. 6 and 8 illustrate the last folding stage. The folding ribs 111^a and 111^b are mounted on the inside of folder board 113 and the projecting ends of the cartridge are brought first one 10 against rib 111^a and then the other against rib 111^b, with the result that one is forced down flat and then the other is forced down on the first. The pedal frame 100 carries hammers 112, operation of the pedal frame 15 causes the hammers to strike the cartridges in the position "D" at the same time that the cartridges in the position "C" are folded. In position "E" of the cartridge no operation takes place; but between position "E" and position "F" the releasing 20 operation takes place as heretofore described.

Claims.

1. A cartridge loading machine, comprising in combination a cartridge holder, means for feeding filler to a cartridge in the holder, a vertically movable tamper, means to lift the tamper, a feed controlling means, and means controlled by the position 30 of the tamper to actuate said feed controlling means.

2. A cartridge loading machine, comprising in combination a plurality of cartridge holders, means for feeding filler to cartridges in the holders, individual vertically movable tampers for the cartridge holders, a common means for lifting all the tampers, individual feed controlling means for each cartridge holder and tamper, and individual means each controlled by the position 40 of one tamper to actuate the corresponding feed controlling means.

3. A cartridge loading machine, comprising in combination a plurality of cartridge holders, means for feeding filler to cartridges in the holders, a vertically reciprocating frame above the cartridge holders, a plurality of vertical tampers loose in said frame one for each cartridge holder, means 45 on the frame and tampers for lifting the tampers, individual means on the frame for each tamper to hang up each tamper on the frame, an individual feed control for each cartridge holder, and individual means 50 actuated by each tamper adapted to control the individual feed controls.

4. A cartridge loading machine, comprising in combination a plurality of cartridge holders arranged in a horizontal row and 55 adapted to receive open ended cartridges in vertical positions, means for feeding filler to the cartridges, a vertically reciprocating frame above the row of cartridge holders, a plurality of plungers one above each holder adapted to drop upon the filler

fed into the cartridge, means whereby the reciprocating frame lifts the plungers to a uniform uppermost position on its upward stroke, individual means on the frame and plunger adapted to engage when the plunger rests upon a filled cartridge and to cause the individual plungers to be raised above their normal strokes, individual means for controlling the feed to each cartridge in each holder, and individual means 70 actuated by the plungers on their said higher stroke to operate the feed controlling means.

5. A cartridge loading machine, comprising in combination a cartridge holder, a tamper movable into and out of a cartridge in the holder, means for feeding filler to a cartridge in the holder, a feed controlling means, and means controlled by the position 80 of the tamper to actuate said feed controlling means.

6. A cartridge loading machine, comprising in combination a cartridge holder, means for feeding filler to a cartridge in the holder, a vertically reciprocating frame 90 above the holder, a vertical tamper loose in the frame, means for lifting the tamper with the frame, means on the frame for hanging up the tamper, a feed control, and means actuated by the tamper when hung 95 up on the frame to actuate the feed control.

7. A cartridge loading machine, comprising in combination a cartridge holder adapted to receive a cartridge in vertical position, means for feeding filler to the cartridge, a vertically reciprocating frame above the holder, a vertical plunger above the holder adapted to drop upon the filler fed into the cartridge, means whereby the reciprocating frame lifts the plunger on its upward 105 stroke, means on the frame and plunger adapted to engage when the plunger rests upon a filled cartridge and to cause the plunger to be raised above its normal stroke, means for controlling the filler feed, and 110 means actuated by the plunger on its said higher stroke to operate the feed controlling means.

8. A cartridge loading machine, comprising in combination a plurality of cartridge 115 holders, means for feeding filler to cartridges in the holders, a vertically reciprocating frame, means whereby the frame normally lifts all the plungers to a uniform upper position, individual means on the 120 frame for hanging up each tamper on the frame when it rests on a filled cartridge, an individual feed control for each cartridge holder, and individual means actuated by each tamper when hung up on the frame 125 to control the individual feed controls.

9. A cartridge loading machine, comprising in combination a plurality of cartridge holders, means for feeding filler to cartridges in the holders, a vertically recipro- 130

eating frame, means whereby the frame normally lifts all the plungers to a uniform upper position, individual means on the frame for hanging up each tamper on the

5 frame when it rests on a filled cartridge, an individual feed control for each cartridge holder, individual means actuated by each tamper when hung up on the reciprocating frame to actuate the feed control to
10 shut off the feed to the corresponding cartridge, and common means adapted for manual operation to release all the plunger hangers and to actuate all the feed controls to open all the feeds.

15 10. A cartridge loading machine comprising a plurality of cartridge holders arranged in a horizontal row and adapted to receive open ended cartridges in vertical positions, means for feeding filler to the cartridges, a vertically reciprocating frame above the row of cartridge holders, a plurality of plungers one above each holder adapted to drop upon the filler fed into the cartridge, a collar upon each plunger, a spring board on the reciprocating frame upon which the collar is adapted to rest, so that the reciprocating frame raises the plungers to a uniform uppermost position on its upward stroke, a hanger finger pivoted upon the reciprocating frame one for each plunger, the upper end of the hanger finger adapted to move beneath said collar when the plunger rests upon a filled cartridge, the subsequent upward movement of the reciprocating frame carrying the plunger to a position above its normal stroke, individual feed controls for each cartridge holder, and individual means actuated by each plunger when hung up on its hanger finger to actuate said feed control.

11. A cartridge loading machine, comprising a plurality of cartridge holders arranged in a horizontal row and adapted to receive open ended cartridges in vertical positions, means for feeding filler to the cartridges, a vertically reciprocating frame above the row of cartridge holders, a plurality of plungers one above each holder adapted to drop upon the filler fed into the cartridge, a collar upon each plunger, a spring board on the reciprocating frame upon which the collar is adapted to rest, so that the reciprocating frame raises the plungers to a uniform uppermost position on its upward stroke, a hanger finger pivoted upon the reciprocating frame one for each plunger, the upper end of the hanger fingers adapted to move beneath said collar when the plunger rests upon a filled cartridge, the subsequent upward movement of the reciprocating frame carrying the plunger to a position above its normal stroke, individual feed controls for each cartridge holder, and individual means actuated by each plunger when hung up on

its hanger finger to actuate said feed control, said feed control involving a feed gate, and said feed control actuating means involving a pivoted lever connected with said gate and weighted to normally hold said gate open, and a detent finger adapted to enter beneath said lever when said lever is raised by the upward action of the collar on the plunger. 70

12. A cartridge loading machine, comprising a plurality of cartridge holders arranged in a horizontal row and adapted to receive open ended cartridges in vertical positions, means for feeding filler to the cartridges, a vertically reciprocating frame above the row of cartridge holders, a plurality of plungers one above each holder adapted to drop upon the filler fed into the cartridges, a collar upon each plunger, a spring board on the reciprocating frame upon which the collar is adapted to rest, so that the reciprocating frame raises the plungers to a uniform uppermost position on its upward stroke, a hanger finger pivoted upon the reciprocating frame one for each plunger, the upper end of the hanger finger adapted to move beneath said collar when the plunger rests upon a filled cartridge, the subsequent upward movement of the reciprocating frame carrying the plunger to a position above its normal stroke, individual feed controls for each cartridge holder, individual means actuated by each plunger when hung up on its hanger finger to actuate said feed control, said feed control involving a feed gate, and said feed control actuating means involving a pivoted lever connected with said gate and weighted to normally hold said gate open, and a detent finger adapted to enter beneath said lever when said lever is raised by the upward action of the collar on the plunger, and manually operable means common to all of the detent fingers and common to all of the hanger fingers to move said detent fingers and said hanger fingers to their normal positions releasing the gate controlling levers and the plungers.

13. A cartridge loading machine comprising a plurality of cartridge holders arranged in a horizontal row and adapted to receive open ended cartridges in vertical positions, means for feeding filler to the cartridges, a vertically reciprocating frame above the row of cartridge holders, a plurality of plungers one above each holder adapted to drop upon the filler fed into the cartridges, a collar upon each plunger, a spring board on the reciprocating frame upon which the collar is adapted to rest, so that the reciprocating frame raises the plungers to a uniform uppermost position on its upward stroke, a hanger finger pivoted upon the reciprocating frame one for each plunger, the upper end of the hanger finger adapted to move beneath said collar when the plunger rests 115 120 125 130

upon a filled cartridge, the subsequent upward movement of the reciprocating frame carrying the plunger to a position above its normal stroke, individual feed controls for each cartridge holder, individual means actuated by each plunger when hung up on its hanger finger to actuate said feed control, said feed control including an individual gate for each cartridge holder, said feed control actuating means including an individual lever pivoted in a horizontal position above each of the plungers and connected to the corresponding gate, said lever being weighted so that its end over the plunger normally inclines downwardly, the connection with the gate being such that the gate is normally open, a pivoted carrier carrying loosely a plurality of individual detent fingers adapted to individually move on the carrier to move in under the individual levers when they are lifted by the upward stroke of the corresponding plunger when supported on the corresponding hanger finger, a movable bar adapted to strike all the pivoted hanger fingers to remove them from beneath the collars on the plungers, and connection between said bar and the detent finger carrier so that when said bar is operated the carrier is operated to withdraw all the detent fingers from beneath the levers.

14. A cartridge loading machine comprising in combination a main supporting frame, oscillating levers mounted on the frame, a vertically reciprocating cross head frame working in vertical ways in the main frame and connected with said oscillating levers, a horizontal row of cartridge holders below said cross head frame, said holders adapted to receive open ended cartridges in vertical positions, a tamper plunger above each of the cartridge holders, said tamper plungers passing loosely through the cross head frame, a spring board upon the upper

side of the cross head frame for each of the plungers, each plunger having a collar adapted to rest upon its corresponding spring board, a vertical pivoted hanger finger upon the cross head frame for each of the plungers, the upper end of each hanger finger adapted to move under the collar of the corresponding plunger when that plunger rests upon a filled cartridge, means for feeding filler to cartridges in the cartridge holders, including a feed belt driven from the oscillating levers, individual feed control means including a gate for each cartridge holder, feed control actuating means including individual pivoted levers connected at one end to the corresponding gates, being pivoted centrally and being weighted at their other ends to normally hold said gates open, said levers being pivoted one above each of the plungers so that their weighted ends will be lifted when the plungers are hung up on their hanger fingers, a detent finger carrier pivotally mounted in the main frame, individual detent fingers one for each gate actuating lever adapted to individually move on the carrier to drop under the corresponding levers when raised by the plungers, a striker bar pivotally carried on the main frame and adapted to strike on the hanger fingers to move them from beneath the plunger collars, and connecting means between said striker bar and the detent finger carrier to move the carrier to remove all the detent fingers from beneath the gate control levers.

In witness that I claim the foregoing I have hereunto subscribed my name this ninth day of December, 1913.

JAMES F. O'BRIEN.
